UNITED STATES PATENT OFFICE.

FRANKLIN L. LANE, OF BELOIT, WISCONSIN, ASSIGNOR TO THE BERLIN MACHINE WORKS, OF BELOIT, WISCONSIN, A CORPORATION OF WISCONSIN.

PLANER-KNIFE HOLDING DEVICE.

1,010,645.

Specification of Letters Patent.

Patented Dec. 5, 1911.

Application filed August 15, 1910. Serial No. 577,346.

To all whom it may concern:

Be it known that I, FRANKLIN L. LANE, a citizen of the United States, residing at Beloit, in the county of Rock and State of Wisconsin, have invented certain new and useful Improvements in Planer-Knife-Holding Devices, of which the following is a specification.

The main object of this invention is the provision of a simple means for holding planer knives in their cylinders which will securely maintain the knives in proper working position without danger of becoming loose or ineffective in their knife-holding function.

Another salient feature of the invention is the production of a holding means of this character which will be particularly simple in construction and economical to manufacture.

On the accompanying drawing, which forms a part of this specification, I have illustrated a desirable embodiment of this invention and in such drawing, Figure 1 is a section through a planer cylinder equipped with one form of my improved knife holding means, some of the wedge blocks being shown in section, others being shown in full lines, while still another is omitted to more clearly indicate the construction. Fig. 2 is a plan view of a planer cylinder supplied with the improved holding means, and Fig. 3 is a perspective view of one of the cylindrical wedge blocks.

By reference to this drawing it will be noticed that the planer cylinder, 10, is supplied with a plurality of longitudinally disposed recesses 11, along its periphery and supplied for the purpose of accommodating the various planer knives 12. Adjacent to each of such knife recesses and opening into or communicating therewith, I supply the cylinder with a plurality of cylindrical cavities 13, extended inwardly from the outer face of the cylinder, as is clearly illustrated. Each of such cavities is adapted and intended to accommodate and receive a cylindrical wedge block 14, one side of which is cut away or beveled at 15, to provide a wedge surface adapted to apply pressure on the knife 12, to hold the same in its recess against movement or displacement. The outer surface 16, of each of such wedge blocks is preferably curved to conform to the cylindrical surface of the cylinder 10.

Each of such wedge blocks has a substantially central recess or aperture 17, extended therethrough, such aperture being enlarged at 18, at its outer end for the accommodation of the head 19, of a holding or adjusting screw 20, which extends through the hole 17 and cooperates with the threads of a screw-threaded hole or extension 21 in the cylinder at the base of the cavity 13. As I have clearly shown, the head 19 of the screw bears against the shoulder in the block at the junction of the parts 17 and 18 of the aperture extended therethrough. In order to facilitate the removal of such wedge blocks from their receiving cavities when the screws have been removed, each is equipped with a recess or hole 22, into which the end of a hook or other removing means may be applied to effect such removal.

The parts are assembled by placing the knife 12 in its recess 11, inserting the wedge blocks 14 in their cavities 13, with the wedge surfaces 15 against the knives 12, and then introducing the retaining screws 20, which act to force the wedge blocks inwardly and clamp the knife between themselves and the opposite wall of the recess 11, all as will be readily understood by those skilled in this art. It will be noticed that in reality, these knives are held in place by two cooperating wedges, the screw threads of the screws 20 constituting one wedge means, the beveled faces of the blocks 14 representing the other co-acting wedge. It should be noticed that because the cavities 13 are of cylindrical form, they may be readily drilled into the cylinder; also the wedge blocks 14, owing to their general cylindrical form, can be provided at a minimum expense. Another feature of advantage of this construction resides in the fact that no portion of the holding means for the knives projects outwardly beyond the periphery or cylindrical surface of the cylinder.

Whereas I have herein indicated one particular embodiment of the invention, I wish to have it understood that the invention is susceptible of embodiment in a considerable variety of forms and that it is therefore not limited to the precise and exact features of structure mentioned and illustrated in connection with this particular form of holding means. It will be apparent therefore, that without departure from the substance and essence of the invention, many minor

mechanical changes may be made in the parts illustrated and described.

I claim:

- 5 1. In a construction of the character described, the combination of a planer cylinder having a knife-receiving recess, a knife in said recess, a cylindrical cavity in said cylinder inclined toward said recess and communicating with said recess, a cylindrical block in said cavity, said block being cut off to provide a wedge surface on one side adapted to apply a holding pressure on said knife, and means to adjust said wedge block, substantially as described.
- 10 2. In a construction of the character described, the combination of a planer cylinder having a knife-receiving recess, a knife in said recess, a cylindrical cavity in said cylinder intersecting said recess, a cylindrical block in said cavity cut off to provide a wedge surface on one side adapted to apply a holding pressure on said knife, and screw means parallel with the axis of said wedge block adapted to adjust said wedge block, substantially as described.
- 15 3. In a construction of the class described, the combination of a planer cylinder having a knife-receiving recess, a knife in said recess, a cylindrical cavity in said cylinder intersecting said recess, an apertured cylindrical block in said cavity and cut off to provide a wedge surface on one side adapted to apply a holding pressure on said knife, said cylinder having a screw threaded hole at the base of said cavity, and a block-adjusting screw extended axially through the aperture of said cylindrical block and cooperating with the threads of said hole, substantially as described.
- 20 4. In a construction of the character described, the combination of a planer cylinder having a knife-receiving recess, a knife in said recess, a cylindrical cavity in said cylinder inclined toward said recess and intersecting said recess, a cylindrical block in said cavity cut off to provide a wedge surface on one side and adapted to apply a holding pressure on the knife, said cylinder having a screw threaded hole at the base of said cavity, said cylindrical block having an aperture extended therethrough parallel with

the axis of the block with an enlargement at its outer portion, and a headed block-adjusting screw coöperating with the threads of said hole, the head of said screw being accommodated in said enlargement and bearing against the shoulder of the block at the junction of said block aperture and its enlargement, substantially as described.

55

5. The combination of a planer cylinder having a knife-receiving recess, a cylindrical cavity in said cylinder intersecting said recess, the axis of said cavity and the plane of said recess converging inwardly, a cylindrical block in said cavity having a side flattened to exert holding pressure on a knife in said recess, and a screw for adjusting said block.

60

6. The combination of a planer cylinder having a knife-receiving recess, a cylindrical cavity in said cylinder intersecting said recess, the axis of said cavity and the plane of said recess converging, a cylindrical block in said cavity having a side flattened to engage the knife, and a screw for adjusting said block.

65

7. The combination of a planer cylinder having a knife-receiving recess, a cylindrical cavity in said cylinder intersecting said recess, the cavity and recess converging inwardly, a cylindrical block in said cavity having a flattened portion to engage the knife, and a screw having threaded engagement with said cylinder and extending axially through said cylindrical block for drawing said block inwardly into holding engagement with a knife in said recess.

70

8. The combination of a planer cylinder having a knife-receiving recess, a cylindrical cavity in said cylinder intersecting said recess, the cavity and recess converging, a cylindrical block in said cavity having a flattened portion to engage the knife, and a screw engaging said planer cylinder and extending axially through said cylindrical block for forcing the latter longitudinally of said cavity into knife holding and releasing positions.
